United States Patent Office.

WILLIAM HUNTER, OF DETROIT, MICHIGAN.

Letters Patent No. 70,851, dated November 12, 1867; antedated November 4, 1867.

IMPROVED PADDLE-WHEEL.

The Schedule referred to in these Letters Patent and making part of the same.

TO ALL WHOM IT MAY CONCERN:

Be it known that I, WILLIAM HUNTER, of Detroit, in the county of Wayne, and State of Michigan, have invented a new and useful improvement in Propelling-Wheels for Steamboats; and I do hereby declare that the following is a full, clear, and exact description of the same, reference being had to the annexed drawings, making part of this specification, in which—

Figure 1 is a perspective view, and

Figure 2 is a vertical section.

The same letters are employed in the indication of identical parts in both figures.

A is the hub or centre, to which the radial arms B are attached, securely held in their relative positions by the rim C, which passes around the wheel near the end of the arms, on each set of radial arms, of which there may be two or more. The floats D are flat on their faces, and are bolted to the ends of the radial arms, and to the side of the next preceding arm, or to the rim C, so as to form an angle of about forty degrees to the arm to the end of which they are attached: When these buckets leave the water they will be nearly vertical. The buckets will present a continually pressing surface against the water, and lose no part of their power in raising the bucket from the water, which, in the ordinary wheel, is consumed in lifting the water upon the face of the bucket when rising towards the surface. This form of bucket gives strength to the wheel by diagonally bracing the arms, and it may be easily and cheaply adopted upon any ordinary paddle-wheel.

I am aware that numerous feathering-buckets are so arranged as to stand nearly vertical when leaving the water; and I do not, therefore, claim this position of the buckets under all conditions; but what I claim as my invention, and desire to secure by Letters Patent, is—

A paddle-wheel constructed with radial arms B and floats D, which are rigidly attached to the end of one arm, and, extending in front thereof, are secured on the opposite edge of the next preceding arm, or to the rim C, in such manner as to form an acute angle at its upper edge, and form a diagonal bracing for the arms, substantially as described.

In testimony whereof I have signed my name to this specification in the presence of two subscribing witnesses.

WM. HUNTER.
